OPEN COOLING BOXES OF METALLURGICAL FURNACES, ESPECIALLY OF BLAST FURNACES

Paul Desfossez, Dillingen, Saarland, Germany, assignor to Societe Anonyme des Forges & Acieries de Dilling, Dillingen, Saarland, Germany, a corporation of France

Filed Nov. 3, 1958, Ser. No. 771,376

Claims priority, application France Nov. 4, 1957

6 Claims. (Cl. 266—32)

This invention relates to the cooling boxes used in metallurgical furnaces, especially blast furnaces.

The known means for cooling the linings of metallurgical furnaces include open boxes, closed boxes, boxes with detachable water-cooled parts, and cooling plates having water tubes cast therewith.

These different cooling means, when embedded in the furnace linings, all possess disadvantages, for example rendering it necessary to install special connections for the supply and evacuation of the water, and it is often difficult or even impossible to clean them in order to remove material deposited from the water. Furthermore it is difficult or even impossible to see the interior of the boxes, so that damage which may occur therein can generally be discovered only very late, or not at all, although the failure of the cooling action or the penetration of water into the furnace through the lining which is to be cooled may cause damage involving repairs at very considerable expense.

In order to avoid these disadvantages it has been proposed to cause the cooling water to trickle over the external casing of the furnace, and to dispose in the thickness of the furnace wall, embedded in the lining, open cooling boxes, of which the internal upper wall, visible from the exterior, forms an angle of about 20° with the horizontal. The top of the oblique upper wall of the cooling box is given a form such that it joins the casing of the furnace by a curvature having a radius of at least 30 mm., this curvature facilitating the penetration of the trickling water into the cooling box.

However, it has been observed that a certain quantity of the water which should serve for the cooling action does not reach the inner end of the box, because drops of water fall down from the upper wall at a certain distance from the inner end and are consequently not used for the cooling of this end of the box.

In accordance with the invention, in order to compel the cooling water which trickles over the external casing of the furnace but might not follow the oblique upper wall of the cooling box, to pass to the inner end of the cooling box, there is mounted inside the cooling box a guide plate extending parallel or substantially parallel to the oblique upper wall of the cooling box.

The invention is hereinafter described with reference to the accompanying drawing, which represents diagrammatically, by way of example, a form of embodiment of the invention.

FIG. 1 is a vertical section along the centre line of the box.

FIG. 2 is a front view of the box, and FIG. 3 is a plan view thereof, the centre line being marked I—I.

FIG. 4 is a diagrammatic vertical section of part of a furnace provided with cooling boxes according to the invention.

The cooling box is constituted, as shown in FIG. 1, by a metal sheet 1 of any suitable thickness. To this sheet 1, there is imparted the shape indicated by the vertical section shown in FIG. 1; this is achieved by stamping a single sheet in a die or by welding two sheets together to produce the desired shape. To this sheet there are secured, as by welding, vertical sheets 2 to 6, which impart to the cooling box its external shape and at the same

2

time constitute, in part or entirely, cooling ribs to assist in the transfer of heat. A guide sheet 7, serving to compel the drops of water from the top of the sheet 1 to go to the inner end of the box, is secured inside the box, for example by welding or in a removable manner by any appropriate means.

Thus, in accordance with the example represented in the drawing, this guide plate 7 can be carried by two plates 9 fixed, by any suitable means, for example by welding, 10 on the bottom of the box. These plates 9 are preferably spaced from the side sheets 2 of the box, as shown in FIG. 2, leaving spaces for direct access of the cooling water to the side sheets 2. The top end of the guide plate 7 preferably projects out beyond the casing 8, the 15 projecting part of the plate 7 being shaped so as to form a gullet or intake channel for the cooling water, also intended to guide the cooling water towards the inner end of the box.

Any number of these cooling boxes are fixed in the 20 casing 8 of the furnace, for example by welding, at variable distances apart, circumferentially and/or longitudinally, so as to ensure sufficient cooling of the furnace in each particular case.

The supply of cooling water is preferably effected, as 25 shown in FIG. 4, through one or more conduits comprising atomisation devices 11, and a succession of gutters 12. A single conduit comprising atomisation devices 11, or a single gutter 12, is sufficient to supply abundantly eight rows of the improved cooling boxes situated one 30 below the other, even when the generation of heat is considerable. In case of need, it is obviously possible to install a plurality of conduits comprising atomisation devices 11 or a plurality of gutters 12 at different distances from one another, the cooling water which reaches too 35 high a temperature being drained off through a separate gutter.

Any suitable dimensions desired may be given to the 40 improved cooling boxes. It is of little importance whether their width exceeds their height or vice versa, this problem being solved, in each particular case, only after taking into account the optimum cooling conditions.

The improved cooling box effects a reduction of water 45 consumption and provides excellent cooling of the furnace lining. It possesses great advantages in the case of long furnace runs.

What I claim is:

1. In a furnace, in combination, a furnace side wall having an outer surface and being formed with a recess therein extending inwardly from said outer surface into said wall, said recess having an outer open end at said outer surface and an inner closed end inwardly spaced therefrom and a top surface extending rearwardly and downwardly inclined from said open to said closed end; adjustable guide plate means extending spaced from said 50 top surface of said recess from said open end rearwardly and downwardly inclined toward said closed end of said recess for guiding cooling water trickling down along said outer surface of said furnace wall and dripping downwardly from said top surface of said recess up to the inner closed end of said recess; and mounting means for mounting said guide plate means in said recess movable toward and away from said closed end thereof.

2. In a furnace, in combination, a furnace side wall having an outer surface and being formed with a recess 55 therein extending inwardly from said outer surface into said wall; a cooling box located in said recess and having an outer open end at said outer surface and an inner closed end inwardly spaced therefrom, a substantially horizontal bottom wall and a top wall extending inclined at an acute angle to said bottom wall from said outer 60 open end to said inner closed end of said box and being connected to said bottom wall at said inner closed end,

said top and bottom walls having outer ends flush with said outer surface of said furnace wall; adjustable guide plate means extending substantially parallel to and spaced from said top wall of said box from said open toward said closed end of said box for guiding cooling water trickling down along said outer surface of said furnace wall up and dripping from said top wall of said box to the inner closed end of said box; and mounting means for mounting said guide plate means in said box movable toward and away from said closed end thereof and comprising a pair of support plates extending spaced from each other upwardly from and substantially normal to said bottom wall of said box and being fixedly connected along the upper edges thereof to said guide plate means.

3. In a furnace, in combination, a furnace side wall having an outer surface and being formed with a recess therein extending inwardly from said outer surface into said wall; a cooling box located in said recess and having an outer open end at said outer surface and an inner closed end inwardly spaced therefrom, a substantially horizontal bottom wall and a top wall extending inclined at an acute angle to said bottom wall from said outer open end to said inner closed end of said box and being connected to said bottom wall at said inner closed end, said top and bottom walls having outer ends flush with said outer surface of said furnace wall; a plurality of cooling ribs fixedly connected to said top wall and extending substantially normal thereto upwardly therefrom; guide plate means extending spaced from said top wall of said box from said open end rearwardly and downwardly inclined toward said closed end of said box for guiding cooling water trickling down along said outer surface of said furnace wall and dripping downwardly from said top wall up to the inner closed end of said box; and mounting means for mounting said guide plate means in said box and comprising a pair of support plates extending spaced from each other upwardly from and substantially normal to said bottom wall of said box and being fixedly connected along the upper edges thereof to said guide plate means.

4. In a furnace, in combination, an upright furnace wall having an outer surface and being formed with a plurality of recesses therein arranged spaced from and one below the other and extending each inwardly from said outer surface into said wall; a cooling box located in each of said recesses and having an outer open end at said outer surface and an inner closed end inwardly spaced therefrom, a substantially horizontal bottom wall and a top wall extending inclined at an acute angle to said bottom wall and being joined thereto at said closed end of said box, said top wall having an upwardly curved outer end and blending into said outer surface of said wall and said bottom wall having an outer end flush with said outer surface of said furnace wall; guide plate means in each box extending spaced from and substantially parallel to said top wall thereof from said outer toward said inner end of said box and having an upwardly curved outer end portion extending outwardly beyond said outer surface of said furnace wall and beyond said outer end of said bottom wall; mounting means for mounting said guide plate means in said box; spray means for spraying cooling water at a portion of said outer surface of said furnace wall located above the topmost of said recesses; and a plurality of collecting means arranged between said recesses for collecting cooling water trickling down along said outer surface of said furnace wall and for guiding such cooling water onto said outwardly ex-

tending end portion of said guide plate means, respectively.

5. In a furnace, in combination, a furnace side wall having an outer surface and being formed with a recess therein extending inwardly from said outer surface to said inner wall, said outer surface having an upwardly extending surface portion above said recess and a downwardly extending surface portion below said recess, said recess having an outer open end at said outer surface and an inner closed end inwardly spaced therefrom and a top face extending downwardly and rearwardly inclined at an acute angle to a horizontal plane from said outer open end to said inner closed end of said recess; guide plate means extending within said recess downwardly and rearwardly inclined under an acute angle to a horizontal plane from said outer open end of said recess to a point near said inner closed end thereof so as to leave a passage between its inner end and said inner closed end of said recess; and a source of cooling fluid located in the region above said recess and supplying cooling fluid onto said upwardly extending surface portion of said furnace wall, whereby the thus supplied cooling fluid will flow down said upwardly extending surface portion and into said recess, flowing in said recess partly along said top face thereof and partly dripping from said top face onto said guide plate means, to be directed thereby to the closed rear end of said recess, where all cooling fluid will pass downwardly through said passage between said closed rear end of said recess and said guide plate means and flow out of said recess to then pass downwardly along said downwardly extending surface portion of said furnace wall.

6. In a furnace, in combination, a furnace side wall having an outer surface and being formed with at least one recess therein extending inwardly from said outer surface into said wall, said recess having an outer open end at said outer surface and an inner closed end inwardly spaced therefrom, a substantially horizontal bottom face and a top face extending inclined at an acute angle to said bottom face from said outer open end to said inner closed end of said recess and being connected to said bottom face at said inner closed end, said top and bottom faces having outer ends flush with said outer surface of said furnace wall; guide plate means extending spaced from said top face from said open end rearwardly and downwardly inclined toward but short of said closed end of said recess; and means for supplying cooling fluid onto said outer surface of said furnace wall above said recess, whereby the cooling fluid will flow down along said outer surface and into said recess where it will flow in part downwardly along said top surface and in part dripping from said top surface onto said guide plate means to flow along the latter to said inner closed end of said recess and from there along said bottom face onto the outer surface of the furnace wall below said recess.
